UNITED STATES PATENT OFFICE

CLARENCE V. JOHNSON, OF WICHITA, KANSAS, ASSIGNOR OF ONE-THIRD TO HARRY L. REAM AND ONE-THIRD TO FOUZE KIMBALL, BOTH OF WICHITA, KANSAS

STREET AND HIGHWAY MARKER

Application filed October 7, 1929. Serial No. 397,978.

The invention aims to provide an exceptionally simple and inexpensive, yet an attractive and effective marker for use at various points along highways and streets for the purpose of giving information with regard to other streets or highways or for displaying traffic controlling information such as the words "Caution", "Stop", "Boulevard", "Curve", etc.

10 A further object is to provide a marker or sign which may readily be shipped in large quantities in knock-down form and quickly and easily assembled.

With the foregoing in view, the invention 15 resides in the novel subject matter herein-after described and claimed, description being accomplished by reference to the accompanying drawing.

Fig. 1 is a perspective view.
20 Fig. 2 is a top plan view.

The drawing above briefly described, illustrates the preferred form of construction and while this construction will be herein specifically explained, it is to be understood 25 that within the scope of the invention as claimed, minor variations may be made.

The numeral 3 denotes a post to be set or driven into the ground, said post being preferably although not necessarily formed 30 from a single length of angle iron. Two relatively long and narrow sign plates 4 are disposed in parallel vertical planes and are secured against opposite sides of the post 3, securing bolts 5 being shown passed centrally through one of the sign plates 4 and through one flange of the post 3. The ends 35 of the plates 4 are bent laterally inwardly at right angles as denoted at 6.

Two additional sign plates 7 are disposed 40 in parallel vertical planes at the ends of the plates 4, said plates 7 being secured by bolts or the like 8 against the outer sides of the plate ends 6 above described. The plates 7 are of T-shape with their shanks 9 projecting downwardly beyond the bars 4 and with their heads 10 projecting upwardly and laterally in opposite directions from 45 said plates 4, the ends 11 of said heads being preferably pointed as shown, particularly when the plates are to bear directional

printed matter and arrows, as illustrated in Fig. 1.

The construction shown and described is simple and inexpensive, may be readily shipped in knock-down form and quickly 55 and easily assembled, and it affords a great number of sign faces presented toward four different directions radiating from the post 3, for which reason it is well adapted for a marker at street intersections to give the 60 names of the intersecting streets, the numbers of adjacent blocks and other desirable information.

On account of the existing advantages for the details disclosed, they are preferably 65 followed. However, within the scope of the invention as claimed, variations may be made as above stated.

I claim:—

1. A sign comprising a post, two relatively long and narrow sign plates disposed horizontally and secured in parallel vertical planes against opposite vertical sides of said post, and two additional sign plates disposed in parallel vertical planes transverse to the first named plates, said additional sign plates being secured to the ends of said first named plates and projecting vertically therefrom.

2. A sign comprising a post, two relatively long and narrow sign plates disposed horizontally and secured in parallel vertical planes against opposite vertical sides of said post, and two additional sign plates disposed in parallel vertical planes transverse to the first named plates, said additional sign plates being secured to the ends of said first named plates and projecting both upwardly and downwardly therefrom, the upwardly projecting portions of said additional plates being in the form of T-heads which project laterally in opposite directions from said first named plates.

3. A sign comprising a post, two relatively long and narrow sign plates disposed horizontally and secured between their ends against opposite sides of said post, said plates being disposed in parallel vertical planes and having their ends bent laterally inward at right angles, two additional sign

plates disposed in parallel vertical planes transverse to the first named plates, and means securing said additional plates against the outer sides of said inwardly bent ends of said first named plates.

- 5 4. A sign comprising a post, two relatively long and narrow sign plates disposed horizontally and secured between their ends against opposite sides of said post, said plates being disposed in parallel vertical planes and having their ends bent laterally inward at right angles, two additional sign plates disposed in parallel vertical planes transverse to the first named plates, and
10 means securing said additional plates against the outer sides of said inwardly bent ends of said first named plates, said additional plates being of T-shape with their shanks projecting downwardly from said first
15 named plates and with their heads projecting upwardly and laterally from said first named plates.

In testimony whereof I have hereunto affixed my signature.

CLARENCE V. JOHNSON.
